VEHICLE BODY CLOSURE ASSEMBLY

Elmer Frazier McHenry, St. Louis, Mo.

Application December 27, 1948, Serial No. 67,500

6 Claims. (Cl. 296—143)

1

This invention relates to improvements in vehicle body closure assemblies, and more particularly to improved means for opening and closing an access opening in a motor truck or other vehicle body.

Many present day commercial trucking loads are of such nature as to require a rigid, sturdy, long life closure, such for example as is provided by a series of stakes, in a stake or panel body or other form thereof. Many types of freight are further of such nature as to render it necessary to protect the goods from excess air exchange, as against extreme heating and chilling effects. Among loads of the kinds requiring a rigid and sturdy closure, as well as protection against effects of air and heat exchange, may be noted many package perishables and other food stuffs, and beverages such as beer in cooperage, these being noted merely as examples and without limitation. It is confidently stated in explanation of the present need and the problems presently now overcome, that there has heretofore existed no fully commercially satisfactory closure for truck bodies in service of this kind. The problem is aggravated by the need of frequent stops incident to local deliveries in many cases, and the necessity for avoidance between such stops, of the effects of hot or cold air, while at the same time there exists a strict necessity for protection against loss of the load through a body opening. The invention accordingly has as its principal object, the purpose of overcoming the noted inadequacies of existing vehicle bodies, particularly those in local commercial trucking service.

A further important objective of the invention is realized in an improved flexible closure of curtain type, which is sturdy, fully protective against any appreciable air exchange when used with a panel or other solid type of body, and which in the most advanced embodiment, is positively secured in taut relation, preferably in the vertical plane of the closure.

A further and important objective is realized in an improved arrangement of stake securement and stake captive arrangements, facilitating the removal and reinsertion of the rigid elements of the closure.

Still a further major objective of the present invention is realized in an improved combination closure including both rigid and flexible closure provisions such as stakes and a curtain, so embodied by preference as to result in a compact factory produced package unit susceptible of being shipped, and applied as completely as-

2

sembled, and readily attached to truck bodies of certain existing types.

Additional important objectives include novel features of support, construction and arrangement making for a compact trouble-free assembly of the general type noted, and which may be produced at a low cost and is such as to require virtually no service attention throughout a long period of utility.

The foregoing and numerous other objectives will more clearly appear from the following detailed description of a preferred embodiment of the invention, particularly when considered in connection with the accompanying drawing, in which:

Fig. 1 is a fragmentary rear elevation of a truck body of panel type, the view being isometric in nature and showing the location and general appearance of a preferred form of closure assembly;

Fig. 2 is a fragmentary horizontal sectional detail as taken along line 2—2 of Fig. 1;

Fig. 3 is a substantially enlarged fragmentary end view of a headrail and curtain roller support, together with tops of the stakes, and portions of the vehicle body top, parts of the latter being shown in section;

Fig. 4 is a view somewhat similar to Fig. 3, but taken in a vertical plane intersecting the head bar and curtain roll assembly, and particularly as viewed along line 4—4 of Fig. 1;

Fig. 5 is an enlarged sectional elevation taken in a vertical plane transversely of the upper rear portion of the vehicle body, and showing details of structure of the curtain roll, spring, bearing and support provisions, all as viewed along line 5—5 of Fig. 3, and

Fig. 6 is a horizontal, partly sectional view of the headrail structure taken in a plane below the curtain roller and appurtenances, and particularly as viewed along line 6—6 of Fig. 3.

Referring now by characters of reference to the drawing, and first to Fig. 1, a preferred setting of the present improvements is as a combination closure for the rear body opening serving for loading and unloading purposes and indicated at LO, this being shown as located centrally of the rear end panel of a panel type truck body generally indicated at PB. The top closure of the body is or may be conventional in form and is indicated at T, and is crowned or rounded as at TR, where it meets in sealing relation the upper margins of the panels of the body proper.

A floor or deck F is or may be of usual construction, and is supported by the usual cross sills,

only a rearmost one of which is shown at TS, and is provided with a step aperture SA. As thus far described, the truck body is or may be of known form, but represents a type of body particularly usefully embodying the present improvements.

Proceeding first to describe the provisions for closing or blocking the rear opening LO as by vertical stakes, a suitable plurality of the latter indicated at S, may be conventionally removably positioned in stake sockets at the rear of the deck or floor F. Such a socketing structure may be essentially similar to that shown by Fig. 6, or otherwise formed in accordance with preference. The upper socket-forming structure is formed of a pair of parallel cross bars spaced to an extent slightly greater than the thickness of the stakes which, as appears, will extend therebetween (Fig. 6). A forwardmost bar 10 is preferably in the nature of an angle bar, and is of a length so as to extend endwise somewhat beyond the opening LO. The companion or rearmost bar indicated at 11, is parallel to the bar 10, these elements being bridged by a plurality of cross members 12 welded or otherwise secured to the bars as indicated at 13. These members as will now appear, are so spaced laterally as to provide the stake sockets in the number desired in a manner effectively to block the opening against unauthorized entrance of persons, and at the same time to protect fully against loss of heavy load units such as beer cooperage, heavy boxes, cases and the like.

There is frequently provided interiorly of the panel bodies of the type selected for present discussion, a horizontal metal or wood rail R, securely assembled to the interior of the body, these elements serving as attachment pieces for the metal framework of the door or closure assembly. The general location of the elements R in respect to the closure assembly will appear from Figs. 2, 3 and 6. Extended vertically downwardly from, and welded to the bar 11 at opposite sides of the opening LO, are a pair of vertical guide channels 14 and 15 which, as will appear, constitute guide elements for the opposite lateral margins of the roll curtain later to be described, such edges being guidedly directed by the channel formed by these elements. The channels may be welded to the ends of the bar 11, and the head assembly in turn welded to vertical angles 16 and 17 (Fig. 6), the latter being secured to the adjacent elements R of the body.

Attaching as by bolting, to the forwardmost bar 10, particularly to each of the end extensions thereof, is an L-shaped bearing arm or bracket 20. Attachment of these arms may be made in any suitable manner, as by bolts 21, the brackets serving, as will appear, to support the roller assembly of the curtain which coacts with the stakes to complete the closure of the opening LO.

An advantageous feature of the headrail assembly which may be taken as including the bars 10, 11 and the socket-forming members 12 together with the curtain roller and appurtenances, consists of a captive stake rod 22. This may be formed of a length of simple rod stock, with right angled ends, as best shown by Fig. 6, and indicated at 23, these ends being welded to the vertical part of the angle bar 10. Each of the stakes is provided with a screw eye or eye bolt indicated at 24, engaging one end of a length of a flexible captive element exemplified by chain 25, each chain being provided with a circular end link 26, slidably supported by and hence movable

along the rod 22. It will now have appeared that, incident to removal of any one or a plurality of the stakes, they may be brought to one side of the door opening within the body, and still kept captive and secured against loss, through their retention by means of the chains 25 and the rod 22. They are as easily replaced as removed.

Proceeding now to a description of the curtain and curtain roller assembly, the curtain, indicated generally at 27, is wound over a tubular curtain roller 30, the latter being directly or indirectly supported by the bearing arms 20, hence by the bar 10 of the headrail structure. The curtain 27 preferably consists of a heavy grade of canvas, duck or the like, and treated for waterproofing, weather resistance and longer life. The curtain 27 is characterized by a series of horizontal or transverse pockets or hems 31, which may be formed either by application of a separate layer of fabric suitably stitched in each of these zones, or by stitching together in such zones double layers of the curtain fabric, or otherwise as desired. Located within each of the pockets 31 is a flat narrow reenforcing rod 32 of a suitable metal such as steel stock. It will now be apparent that these cross stays 32 serve to prevent wrinkling of the curtain fabric and its distortion due to wind and other effects, and at the same time assure the retention by the curtain of its full width throughout its length, and its guided engagement with both of the vertical channels. The lower or outer margin of the curtain is provided with an anchorage consisting of a latch, shown as a T-shaped strap 33 which may be stitched to the lower margin of the curtain and the strap of which is provided with a plurality of apertures 34 selectively applicable over a retention pin or the like carried by the rear truck sill or truss TS.

The mounting and appurtenances of the curtain are preferably such as to keep the curtain under tension at all times when closed and latched, whereby to preserve its planar relation and realize fully on its air-sealing effects. One manner in which tensioning of the curtain is accomplished, is illustrated by Fig. 5, in which it will appear that the roller assembly includes a shaft 35, the shaft being journaled in an anti-friction bearing assembly, shown as of ball type and indicated at 36. The outer race of this assembly may be secured by any suitable means (not shown) to the vertical part of the bearing arm 20. Although the shaft 35 may be of equal length to, or greater than the length of the roller, it has been found sufficient to utilize a pair of the shorter shafts 35 as stub shafts, one at each end, in which case the inner end of each stub shaft is welded as at 37 to a circular disc 38 within the roller 30. A similar disc 40 may be welded as shown to the shaft 35, and is in turn secured to the roller 30. In this region the roller is provided with an end plate 41 which forms a guard for the curtain at the end of the useful area of the roller, and at the same time serves as a closure for a shallow cylindrical drum 42 containing a clock-type spring 43. The outer end of spring 43 is secured as by rivet 44, to the shell of the drum 42, and the inner end of the spring 43 is provided with a curled terminal embracing an anchorage pin 45, this latter being secured suitably to the plate 41, and if desired, to the element 40, hence operatively follows the roller 30.

It is a preference that the drum 42 remain stationary during normal operation of the roller from which it will now appear that as the roller

is rotated with the drum 42 anchored, the spring 43 is stressed or loaded, the arrangement of coils in the spring being such that this loading takes place as the curtain 27 is pulled downwardly toward and into its fully closed position. The arrangement is further such that the roller and spring are not ratcheted, whereby the curtain, when down or closed, is kept under constant tension for the purposes noted.

A provision is desirably made for adjusting the loading of the spring 43, hence the winding bias exerted on the curtain. The initial spring loading is determined by the angular relation between drum 42 and shaft 35, the latter being constantly angularly related to the inner end of the spring. For adjusting rotation, the drum 42 is provided with an exterior, coaxial, circular extension 46, within which is an antifriction bearing assembly shown as of ball type and indicated at 47, the inner race of which is attached to or closely engages the shaft 35. Externally of the outer face of the drum is a plurality of tapped socket extensions 50 and 51 adapted for selective engagement by screws 52 and 53 extending through apertures 54 in the bearing arm 20. Although no more than one such screw is strictly necessary, it has been found to conduce to a better balanced relation of parts to employ at least a pair thereof as shown. It will now have become obvious that, for adjustment of the spring with the curtain fully wound on the roller for example, the one or more screws 52, 53 are backed out of the sockets, and to increase the spring bias the drum is rotated with the roller held stationary, in a direction to tighten the spring or wind same about the shaft 35. Any suitable number of the sockets 50, 51 may be provided in order to effect the desired nicety of spring loading adjustment. As shown, the drum may be rotated in a spring-tightening or loosening direction, by half turns, until the desired bias is obtained, following which the screws 52, 53 are reinserted and threaded up.

A valuable feature of the present improvements consists in a positive provision for maintaining the curtain fully taut entirely over the area of the loading opening LO. To this end, the bar 11 of the headrail assembly constitutes what may be termed a ramp, over which the curtain is slidably drawn. The ramp is characterized by a convex surface engaging the curtain as will best appear from Figs. 3 and 4, and if desired, the ramp specifically indicated at 60 (Fig. 4) is so related to the curtain roller that the curtain is tightly drawn over the element 60 at all times except when retracted onto the roller, or substantially so. It should here be noted that the convex surface is desirable in order to minimize abrading and tearing effects on the curtain, and that if desired, the ramp may take the form of a horizontal roller (not shown).

By reason of the location of the curtain roller in a plane substantially forward (in relation to the vehicle and body) of the plane of the closure provided by the curtain, the latter will, just upwardly of the ramp, assume an angular relation as shown by Fig. 4. It is for assurance of this effect that it is preferred to mount the bearing arms 20 over the forward bar 10, and to form or secure the ramp 60 on the rearmost parallel bar 11 of the headrail assembly. By reason of the ramp, and the lateral guides afforded by channels 14 and 15, the curtain is positively constrained to and kept in an approximately uniform plane, being the plane of the closure, at all times. Furthermore, it will appear that the plane of the closure area

of the curtain is closely adjacent the plane of the rear faces of the stakes S, so that the latter serve as rigid vertical reenforcements behind the curtain during all periods of their conjoint usage.

It will have appeared that the headrail assembly, together with or including the curtain roller and bearing arms therefor, and if desired, the vertical guide channels 14, 15, may be completely fabricated at the situs of production, and shipped if necessary to transport them, as package units to the situs of their application to the truck. It will further have appeared that the assembly as described, lends itself with or without minor modifications, to application to a wide variety of vehicle bodies generally, and in some specialized locations for stationary installation.

The operation and manner of usage of the several parts described are thought to have been fully apparent from the detail of description thereof, but it may be noted for completeness that installation of the unit in existing truck bodies need involve no more than attachment of the members 16, 17 to the elements R or their counterparts.

Following installation, the curtain is tested for tension and if adjustment of spring loading be required, the spring 43 is given an increased or decreased initial tension as above described, through the agencies of the one or more screws 52 and the cooperating sockets on the drum 42. In installation, care is taken to assure the vertical relation of the channels 14 and 15 and suitably to anchor same upon or in the rear portion of the floor elements F of the truck body. Their lateral spacing being predetermined in factory assembly, the correct relation between the curtain and the channels as well as all other parts of the assembly, is assured.

The curtain may be readily actuated by releasing its latch consisting of the strap member 33, by withdrawal of its apertured portions from the anchorage pin in the sill TS. It is instantly raised to a disappearing position. The stakes may then be removed in the usual manner for unloading purposes, and replaced prior to the next trip of the vehicle. Following replacement of the stakes, the curtain is usually again closed. It will of course appear as entirely possible and clearly contemplated, that where the nature and conditions of the load permit, either of the paired and normally coacting closures, may be separately employed.

Although the invention has been described by detailed reference to a selected and advanced embodiment, it will be understood that the detail of description is intended solely in an instructive rather than in any limiting sense, numerous variants being possible within the scope of the claims hereunto appended.

60 I claim as my invention:

1. In a curtain and roller assembly to serve as a closure for a loading opening of a vehicle body, a curtain, a tubular roller for the curtain on which the curtain may be wound, a spring drum adjacent one end of the roller, bearing arms for the roller at opposite ends thereof, a spring within the drum and anchored at one of its ends to the drum, the opposite end of the spring having a connection within the roller, the spring drum being provided externally with a plurality of angularly spaced sockets, the roller bearing arm adjacent said drum having a transverse opening therethrough, and a pin element extended through said opening, and adapted to engage a selected one of said sockets for ad-

justably positioning said drum and enabling an angular variation of its position with respect to said arm, whereby to enable adjustment of initial spring tension.

2. In a curtain and roller assembly for use as a movable closure for the access opening of a vehicle body or the like, a roller, a flexible curtain wound over the roller, a spring drum at one end of the roller, a spring within, and having its outer end anchored internally of the drum, the drum having an open side adjacent the roller, bearing arms for the roller near its opposite ends, a plurality of apertures through the bearing arm adjacent said drum, the drum provided with a plurality of threaded sockets opening externally of the drum, screws extending through said apertures of the bearing arm and threadedly engaging said sockets, the drum being provided with a movable closure plate adjacent the end of the roller, said plate being movable with the roller and forming an end guard thereon, and a pin carried by said plate and extending internally of the drum, and constituting an anchorage for the opposite end of said spring.

3. In a vehicle body having an opening lying substantially in a vertical plane, a head rail structure adjacent an upper region of said opening and including a pair of horizontally spaced horizontal bars, cross pieces bridging and interconnecting the bars, one of said bars having its ends extended laterally beyond the opening, a bearing arm carried by and extending above said bar extensions, a spring roller carried by the bearing arms, and a roll curtain wound on said roller.

4. The combination and arrangement of elements as recited by claim 3 but further characterized in that the first said bar of the head rail structure is distinctly horizontally spaced from the roller to form a top ramp on which the curtain is slidably engageably movable.

5. In a closure assembly for the access opening of a closed vehicle body, a head rail structure formed of a pair of horizontally arranged and spaced horizontal bars so that load-engaging means may be arranged between said pair of bars to engage the contents of the vehicle, a curtain roller located above and supported by one of said bars, a curtain ramp carried by the other said bar and slidably engaging said curtain, lateral guide elements extending vertically below the last said bar and serving to receive the mar-

gins of the curtain and to constrain same to a vertical plane, said load-engaging means being located just inwardly of the vehicle, in relation to the plane of the curtain as determined by the curtain guides.

6. In a closure for opening and closing the access opening of a vehicle body, a head rail structure consisting of two parallel bars, a curtain roller above and supported by one of said bars, a ramp carried by the other bar and over which the curtain is slidably movable, a pair of vertical guide channels extending below the ends of said ramp and by which a curtain is laterally guided and positioned in a fixed plane when the curtain is drawn, a curtain carried by and wound on said roller, cross pieces bridging said bars and maintaining same in fixed parallelism, a latch at the lower end of the curtain, a spring operatively connected to the curtain roller and coacting with the latch when the curtain is drawn to maintain the curtain under a continuous tension, the curtain roller being supported forwardly of the cross pieces, and the plane of the curtain when closed, as determined by said guide channels, being rearwardly of and closely parallel to the rearmost of each parallel bars.
